Specification for Design.

Patented Dec. 27, 1921.

Application filed May 26, 1921. Serial No. 472,919. Term of patent 14 years.

To all whom it may concern:

Be it known that I, EDWARD W. MAHAN, a citizen of the United States, residing at Kansas City, in the county of Jackson and State of Missouri, have invented a new, original, and ornamental Design for Oil-Burners, of which the following is a specification, reference being had to the accompanying drawing, forming part thereof.

Figure 1 is a perspective view of an oil burner showing my new design, Fig. 2 is a top view of the same.

What I claim is:

The ornamental design for an oil burner as shown.

EDWARD W. MAHAN.
